(57) **CLAIM**

The ornamental design for a wheeled game platform, as shown and described.

DESCRIPTION

The claimed wheeled game platform is used to support a person in a prone position playing a ball action game.

FIG. 1 is a top plan view of the wheeled game platform showing our new design;

FIG. 2 is a front elevational view thereof;

FIG. 3 is a left side elevational view thereof with the right side elevational view being a mirror image;

FIG. 4 is a rear elevational view thereof;

FIG. 5 is a bottom plan view thereof; and,

FIG. 6 is a perspective view thereof.
